UNITED STATES PATENT OFFICE

CARL WOLFF, OF BREMEN, GERMANY

WARNING AND SOUNDING DEVICE FOR SHIPS

Application filed September 7, 1928, Serial No. 304,568, and in Germany March 9, 1928.

The present invention relates to a warning and sounding device for ships, which is to warn the officer in charge of the ship of the fact, that the ship is approaching shallow water, and which, at the same time, is adapted 5 to indicate the depth of water in shallow waters. Devices of a similar type are known, and consist of a rod articulated in the median vertical plane of the ship in front of the bow 10 or below the bottom of the ship in a vertical position or at an angle. This rod may be swung around its point of articulation and thereby indicate the shallow water. Very complicated devices are required for fixing 15 such sounding rods in front of the vessel, and this method is applicable to relatively small vessels only. A sounding rod articulated by one end below the ship is suitable only to small size vessels and to low travelling speeds, 20 since the water current, caused by the travelling motion of the ship relatively, will act upon the sounding rod and cause it to swing upwards.

A further drawback of a sounding rod of 25 this type, articulated to the bottom of a vessel, consists in that comparatively complicated constructions inside the vessel are necessary. In the known arrangement and in its position of rest, the sounding rod below 30 the bottom of the ship is lying close to the bottom of the ship, which constitutes a further drawback, considering that many ships enter into tidal harbours, or, at least, will sometimes get aground near the key walls, 35 causing injury to the sounding rod or even to the ship's bottom. Such injuries may also happen when going into dock.

The present invention removes these drawbacks in this way, that, according to the invention, the warning and sounding device 40 has been provided with special means of fitting such a sounding rod at the side of the vessel, near the bottom thereof, said means also adapted to keep the sounding rod in a sufficient depth in the water even in case of 45 great speeds and large dimensions of the sounding rod, such as required by large size ships.

In this regard it is pointed out, that for 50 reasons of ship-building principles and of

working considerations, the sounding rod should be of relatively light construction and not of too great length. The rod must hang well down, relatively, and should not float upwards easily, notwithstanding its 55 small weight. The sounding rod must not be too long and too heavy in construction, as otherwise large strains will be set up in case of pitching.

According to the invention, further arrangements have been made enabling installation of the device without materially aper- 60 turing the outside hull. Provision has also been made to keep the device well protected in its position of rest, so that injuries to same 65 may not easily occur.

In the drawings accompanying the specification and forming part thereof, the invention has been disclosed diagrammatically by way of example, and

Fig. 1 is a side elevation of the ship with 70 the device forming the object of the invention,

Fig. 2 is a side elevation of a part of the device, on an enlarged scale,

Fig. 3 is a plan view of this part afore- 75 said,

Fig. 4 is a side view of the lower part of the object of the invention in working position,

Fig. 5 is a cross section through the upper 80 portion of the object of the invention, showing the installation of the device at the ship,

Fig. 6 is a cross section through a ship's body with a slightly modified form of the invention, showing a further type of installa- 85 tion,

Fig. 7 is a cross section on line VII—VII in Fig. 6, on an enlarged scale,

Fig. 8 is a plan view of a rolling chock 90 of a vessel with the mechanism for operating the device according to the invention.

At a ship's body or hull 1, at the side of same and preferably below the rolling chock 2, a sounding rod 3 is articulated at point 4 so that it may be swung in a plurality of planes. This sounding rod consists prefer- 95 ably of two narrow blades 5, formed, to ad- vantage, on the principle of stream lines, and held by means of cross stays 6. Heavy brackets 7, 8 have been provided at the hull 100

or rolling chock for fixing purposes, and enabling Cardan support of one end of the sounding rod. To this end there is, e. g., a head member 9 positioned horizontally pivotable in the brackets 7 and 8 by means of a bolt 10, and provided at head member 9 are trunnions 11, on which are mounted the blades 5 so that they may be swung about in a vertical direction.

11 The bolt 10 is bored through in order to carry a connecting organ between the sounding rod and a known indicating device I on the bridge. This connecting member may be connected in any manner directly to the 15 sounding rod, and may indicate at the indicating device I the raising or lowering of the extreme end of the rod.

In Figs. 2 and 3, a modified construction 20 of a specially useful connection between such a connecting member and the sounding rod is shown. In this case an intermediate member in the form of a coulisse 12 has been provided, which coulisse receives a sliding block 13 and is formed with a guiding portion 14, block 13 being fixed to the sounding rod, whereas the guiding member 14 is mounted to slide vertically in a corresponding guide 15 of head member 9. A strengthening rib 16 has been provided for the purpose of 25 stiffening this part as much as possible, as it is subjected to considerable stresses. The lower end 17 of the intermediate member or part is connected, by means of an arm 18, to a rod 19, which extends through the bolt 10 and enters into a gland 20 inside the ship. The parts joining at this point and serving for connection with the indicating device, 30 may be executed as a rod system or as a rope pull. A protective body 21 is advantageously 40 fitted at the forward side of head member 9.

A special advantage is obtained, if at the sounding rod one or several sheering bodies 22 are fitted so as to keep the sounding rod at a comparatively large angle, under the 45 action of the travelling current, to the bottom of the ship. To the end of the sounding rod a hauling means 23 has been fixed, by means of which it is possible to haul up, through the action of a winch W, the sounding rod until it is in a horizontal position and lies close to the ship's bottom. This hauling means also serves for limiting the position 50 of greatest angle of the sounding rod to the ship's bottom.

55 In a specially advantageous modification of the construction, the sheering bodies are arranged between the blades of the sounding rod pivotable around a turning point 24 so that, with the sounding rod in a lowered position, they will take up automatically and approximately the position shown in Fig. 4, whereas in hauling up the sounding rod, they will fold in flat between the blades of the sounding rod. In order to obtain this result, 60 the sheering bodies are supported outside of

their middle, and the forward end of same has been weighted artificially.

The effective surface of the sheering body has been advantageously calculated so, that with the ship's speeds in question, the sounding rod will be kept at about the same angle, 70 this being possible in view of the fact, that the buoyancy of the sounding rod becomes less with reduced speed at the same ratio, as also the effect of the sheering surface becomes less with reduced speed.

In order to hold the sounding rod, in its position of rest, with full certainty, so that also a very heavy pitching of the ship will not cause any injury to the sounding rod or to 80 the ship, and so that no injury can be done to the ship when going astern or when docking, a special support or bearing has been devised for the sounding rod.

With this style of construction there is no 85 necessity of penetrating the ship's hull at any place, and the sounding rod may be taken off and put in place again at any time, also during the voyage and when the ship is underway, for the purpose of control.

90 It is also possible to install, instead of the mechanical indication by the angular position of the sounding rod, also a pneumatic or hydraulic sounding device, e. g. a so-called Heyn's patent sounding device, at the extreme end of the sounding rod, as is indicated at 33, which device is connected in the known manner to the indicating device by means of a hose 34. In this manner the depth 95 of the water is indicated directly, and the sounding rod will at the same time prevent, if the ship is underway, the hydraulic or pneumatic sounding device from floating upwards.

100 In the modification example shown in the drawings, the rolling chock 2 has been provided with a number of angle pieces 25, and the hauling means 23 is carried through an aperture 27 in the rolling chock, said aperture being advantageously lined with wood 26. 110 In consequence of this arrangement, the sounding rod is hauled to close below the rolling chock, the angle pieces will enter between the blades of the sounding rod, and they will keep the sounding rod and retain 115 it also in the case of lateral stresses through pitching.

120 In another modification of the device according to the invention, an arrangement has been made enabling a very convenient and simple fixing of the sounding rod to the ship's hull, under suitable circumstances even without docking the ship, the operation being also carried out at sea. To this end, a fixing member, e. g. an angular organ 28, is 125 provided, with a shoulder 29 arranged inside the angle. This shoulder is intended to grip behind the bulb or roll of the rolling chock, as is shown in Fig. 6. One portion 28' lies against the ship's wall and is connected by 130

means of a pulling member, e. g. by the half round iron 30, to the upper part of the ship's body, a tensioning organ being cut-in near the railing. The other part 28" of the angular body 28 serves to place and support one end of the sounding rod in this way, for example, that an organ similar to member 9 in Figs. 2 and 3 is pivoted here by means of a suitably heavy bolt. The inside of the angular member 28 as well as that of the half round iron 30 is provided with a keyway 31, in which is guided a tensioning organ 32 serving at the same time as a connection between the sounding rod and the indicating device 13 on the bridge.

Attention is particularly directed to the fact that the bolt 10 on which the head numbered 9 is swiveled and the trunnions 11 for receiving the rod 5 form a means for universally connecting one end of the rod in proximity to the side of the pipe near the bottom thereof. In one form, namely, Fig. 5, the brackets 7 and 8 support the bolt and head member while in the form shown in Fig. 6 the parts 25 30, 28 and 28" support the bolt and head member to accomplish a similar purpose.

I claim:

1. Warning and sounding device for ships, comprising in combination, a ship, a sounding rod, means for universally connecting one end of the sounding rod in proximity to the side of the ship and near the bottom thereof, an indicating device on board the ship, a connecting organ between the supported end of the sounding rod and the indicating device, and a hauling organ at the extreme end of the sounding rod.

2. Warning and sounding device for ships, comprising in combination, a ship, a sounding rod, a head to which one end of the rod is connected for vertical movement, means for swiveling the head in proximity to the side of the ship and near the bottom thereof, an indicating device on board the ship, an organ connected to the indicating device and movably mounted at the supported end of the sounding rod, a member slidably mounted on the head and forming an intermediate connection between the organ and the sounding rod, and a hauling organ at the extreme end of the sounding rod.

3. Warning and sounding device for ships, comprising in combination, a ship, a sounding rod, means for universally connecting one end of the sounding rod in proximity to the side of the ship and near the bottom thereof, an indicating device on board the ship, an organ having one end operably connected with the indicating device and slidably mounted through the universal connecting means, a member slidably mounted on the head and fixed to the organ and slidably connected to the sounding rod, a protective structure in front of the head, and a hauling organ at the extreme end of the sounding rod.

4. Warning and sounding device for ships, comprising in combination, a ship, a sounding rod, means for universally connecting one end of the sounding rod in proximity to the side of the ship and near the bottom thereof, 76 sheering bodies on the sounding rod adapted to prevent said sounding rod from floating upwards through the effect of the travelling current, an indicating device on board the ship, an organ having one end operably connected with the indicating device and slidably mounted through the universal connecting means, a member slidably mounted on the head and fixed to the organ and slidably connected to the sounding rod, and a 80 hauling organ at the extreme end of the sounding rod.

5. Warning and sounding device for ships, comprising in combination, a ship, a sounding rod, means for universally connecting 85 one end of the sounding rod in proximity to the side of the ship and near the bottom thereof, rotary and automatically self-adjusting sheering bodies on the sounding rod, said sheering bodies adapted to prevent said sounding rod from floating upwards through the effect of the travelling current, an indicating device on board the ship, a connecting organ between the supported end of the sounding rod and the indicating device, a 90 member slidably mounted in the said head, said member connected with the connecting organ and having a slidably engagement with the sounding rod, and a hauling device at the extreme end of the sounding rod. 100

In testimony whereof I affix my signature.
CARL WOLFF.
